UNITED STATES PATENT OFFICE.

HENRY E. RATHBUN, OF WORCESTER, MASSACHUSETTS.

PORCH SHADE OR BLIND.

1,301,603.

Specification of Letters Patent. Patented Apr. 22, 1919.

Original application filed February 25, 1915, Serial No. 10,583. Divided and this application filed May 24, 1916. Serial No. 99,529.

To all whom it may concern:

Be it known that I, HENRY E. RATHBUN, a citizen of the United States, residing at Worcester, in the county of Worcester and State of Massachusetts, have invented certain new and useful Improvements in Porch Shades or Blinds, of which the following is a specification.

My invention relates to a porch shade, or blind, and more particularly to the cord and pulley attachment of a porch shade or blind, of the class where there are a series of strips or slats secured together and held in place by strands, and having a top edge and a bottom edge, and adapted to be rolled, or drawn up, and held in its rolled or drawn up position by means of cords and pulleys, the pulleys being attached preferably to the top edge of the shade.

20 The object of my invention is to provide an improved cord and pulley mechanism for porch shades and blinds of the class referred to.

This application is a division of my application Serial No. 10,583, filed February 25, 1915.

My invention consists in certain novel features of construction of my improvements, as will be hereinafter fully described.

30 Referring to the drawing:—

Figure 1 is a front view of the upper part of a porch shade or blind, with my improved cord and pulley attachment combined therewith.

35 Fig. 2 is a rear view of the parts shown in Fig. 1.

Fig. 3 is a section, on line 3, 3, Fig. 1, looking in the direction of arrow *a*, same figure.

40 Fig. 4 shows, on an enlarged scale, a cord holder detached, and the enlarged end of a cord secured therein.

Fig. 5 corresponds to Fig. 4, but shows the end of the cord raised, and in its detachable position.

In the accompanying drawing, 1 are flat strips or slats which form the body of the shade, 2 are flexible strands which extend upon opposite sides of the slats in the usual 50 and well known way, to secure said slats together and hold them in position. 3 is the top edge of the shade, consisting in this instance of three strips or slats, having their contiguous faces corrugated or grooved longitudinally, to secure the upper ends of the

strands 2, which pass between them. The strips or slats 3 are secured together in this instance by rivets 4.

There are in this instance three pulley frames 5, 6, and 7, located on the front of the shade, at the top edge 3, and secured to said edge. The pulley frame 5 has a single pulley roll, as shown in Fig. 3, and the pulley frames 6 and 7 have two pulley rolls. The pulley rolls are preferably made of metal with a grooved periphery, and preferably have a rotary movement in their supporting frame. The pulley frame 7, holding two pulleys, is preferably located at or near the end of the top edge 3, as shown in Fig. 1.

Through a loop extension on each pulley frame 5, 6, and 7, passes a two prong metal staple 8, preferably of wire, and of loop shape. The free ends of the staples 8 pass through openings in the top edge 3, to secure the pulleys thereto, and upon the opposite side of the top edge are bent outwardly, and in this instance act to secure my improved cord holder 9 to the top edge 3 of the shade, by passing through two eyes 9' in the upper end of said holder.

The cord holder 9 is located upon the rear side of the shade or blind, and is preferably made of wire and of open end loop shape, having its lower end 9'' contracted or of reduced width.

A cord 10, forming a part of the cord mechanism, has a knotted or enlarged end 10' thereon, which is passed through the enlarged part of the holder 9, as shown in Fig. 5, and then drawn down into the contracted part of said holder, as shown in Fig. 4, to be detachably secured to said holder.

A second cord 11 has a knot or enlarged end 11' at its end, see Fig. 2, which is passed through the enlarged part of the holder 9 and drawn down into the contracted part 9'' of said holder, shown at the left in Fig. 2.

The cord 10 extends down at the rear of the shade and around the lower edge, not shown, and up the front side of the shade and over the pulley 5 at the left, Fig. 1, and then over the double pulleys 6, and 7, shown in Fig. 1. The cord 11 corresponds to the cord 10, but passes only over the two double pulleys 6, and 7, shown at the right in Fig. 1.

By means of the cords 10, and 11, the shade is raised or lowered in the usual way, as desired.

In the construction shown in the drawing, the cord holder 9, on the rear of the top edge, is secured thereto by the same staple that secures the pulley on the front side of 5 the top edge, and at the same operation, by bending over the projecting ends or prongs on said staple, which extends through the eyes or openings in said holder. The ends of the cords which are used to raise and 10 lower the shade, are knotted or made with enlarged ends, which are detachably secured to the holder 9, independent of the top edge of the shade, by passing the knot or enlarged end on the cord through the enlarged part 15 of the holder, and then drawing the cord down into the reduced part of the holder, and thus securely attaching the cord to the top edge of the shade, without any liability of its becoming detached, and without making any holes in the top edge of the shade 20 for the cord.

In case of the breaking of the cord, a new cord may be readily substituted by removing

the knotted end of the broken cord from the holder.

It will be understood that the details of construction of my improvements in cord holders for shades or blinds may be varied if desired.

Having thus described my invention, what 30 I claim as new and desire to secure by Letters Patent is:—

A cord and pulley attachment for porch shades or blinds, comprising a pulley frame having a loop extension, and located on one 35 side of the top edge of the shade, and a cord holder having eyes, and located on the other side of said top edge, and a staple passing through the loop extension in said pulley frame, and passing through the eyes in said 40 cord holder, to secure said pulley frame and cord holder to said top edge.

HENRY E. RATHBUN.
